US00D752555S

(12) **United States Design Patent**
Langhammer et al.

(10) **Patent No.:** **US D752,555 S**
(45) **Date of Patent:** **** Mar. 29, 2016**

(54) **REMOTE CONTROL**

(71) Applicant: **Amazon Technologies, Inc.**, Seattle, WA (US)

(72) Inventors: **Heinz-Dominik Langhammer**, San Francisco, CA (US); **Marc Rene Walliser**, San Francisco, CA (US); **Robert Brian Curtis**, San Francisco, CA (US); **Christopher Green**, San Francisco, CA (US)

(73) Assignee: **Amazon Technologies, Inc.**, Seattle, WA (US)

(**) Term: **14 Years**

(21) Appl. No.: **29/503,750**

(22) Filed: **Sep. 29, 2014**

(51) **LOC (10) Cl.** **14-03**

(52) **U.S. Cl.**

USPC **D14/218**

(58) **Field of Classification Search**

USPC D14/218, 349, 480.5; D13/168, 173, D13/162, 162.1, 166, 171, 174

CPC H04N 5/4403; H04N 5/765; G08C 23/04
